UNITED STATES PATENT OFFICE.

DANIEL W. SMITH, OF MACHIAS, MAINE.

BUCKSAW.

1,253,898.

Specification of Letters Patent. Patented Jan. 15, 1918.

Application filed March 12, 1917. Serial No. 154,300.

To all whom it may concern:

Be it known that I, DANIEL W. SMITH, a citizen of the United States, residing at Machias, in the county of Washington and 5 State of Maine, have invented certain new and useful Improvements in Bucksaws; and I do declare the following to be a full, clear, and exact description of the invention, such as will enable others skilled in the 10 art to which it appertains to make and use the same.

My invention relates to buck saws and has for its object the provision of a frame in which the cross bar is entirely eliminated, 15 thereby permitting the cutting of logs having a far greater diameter than the logs which may be cut with the ordinary buck saws which are in use at the present time.

Another object of my invention is to provide a buck saw frame which is constructed 20 of metal and is substantially arched to give the greatest strength in the frame construction and to entirely eliminate any possibility of the frame becoming warped and in 25 other ways causing numerous annoyances to the operator.

A further object of my invention is to provide a buck saw frame in which all tendency to side buckling is eliminated owing to 30 a novel form of adjusting means provided for the frame.

A still further object of my invention is to provide a frame which is cheap to manufacture, easily assembled and one which 35 gives the maximum of wear with the minimum loss.

To this end my invention resides in the novel construction and combination of parts to be hereinafter described and supplemented 40 by the accompanying drawing which forms a part of this application and in which:

Figure 1 is a side elevation of my improved buck saw; and

45 Fig. 2 is a detail sectional view of my improved manner of adjusting the frame.

My invention comprises a buck saw composed of two substantially arched frame members 1 and 2, the member 1 being less 50 arched than the member 2 and designed to act as a handle for the frame. Between the lower end of the member 2 and connected to the handle member 1 is an ordinary saw blade 3. Any suitable form of connection 55 for this blade member may be used as it forms no part of my invention.

The upper portions of the frame members owing to their arched construction are extended toward each other and have their adjacent ends upturned, the end of the member 1 being bent straight upward as designated at 4 and provided at its upper end with a handle piece 5. The adjacent upturned end 6 of the plate 2 is bent slightly backward upon itself and extending through 65 each of these upturned ends is a bolt 7 having a nut threaded on its outer end to draw the two ends together. Spaced slightly below the bolt 7 is a pair of transversely extending slots 8 in the upturned ends 4 and 6. These slots are in alinement and positioned within these slots and extending between the ends 4 and 6 is a guide member or key 9 provided at the central portion with a laterally projecting stud or pin 10 75 which is adapted to act as a fulcrum point for the locking movement of the two upturned ends when they are drawn together by action of the nut on the bolt 7.

The key 9 is held snugly by the side walls 80 of the slots 8. This positioning of the members 9 prevents any transverse movement of the frame which would tend to side buckling. The slots 8 are of sufficient height as to allow free play of the frame members 85 in respect to the key when the same are rocked either toward or away one another on the fulcrum 10. It is to be understood also that the upper ends are so constructed as to permit play of the moving ends over the bolt 90 7 extending therebetween.

The upturned ends of the two frame members meet at a point spaced from the middle of the frame and adjacent the handle end of the saw frame as clearly illustrated 95 in the accompanying drawings. Owing to the arched construction of my frame, it can be readily seen that the strength of the frame is materially increased and the saw may be utilized for cutting logs of larger 100 dimensions than those that can be cut by the use of the ordinary saw frame having a cross bar extending between the handles as in the present device. The cutting action of the blade will not be in any way impeded until the top of the saw frame comes in contact with the log being operated upon.

While it is understood that this frame may be constructed of any material desired, I have found it preferable to construct the 110 frame of metal piping which comprises the embodiment of my invention in its preferred

form as shown in the accompanying drawings. It will also be understood that I do not limit myself specifically to the arrangement and location of parts as shown and described herein but that all changes may be made in the details of construction of my frame as may be embraced within the scope of the appended claim.

I claim:

10. An arched saw frame formed of a front and a rear section each having a vertical arm extending above the back of the frame, the lower portion of each arm having a vertical slot extending entirely therethrough, 15 the two slots being in alignment longitudinally of the frame, a flat horizontally elongated

plate standing on edge and received in said slots to hold the two sections against lateral canting, lateral projections on the sides of said plate interposed between the lower ends of the two arms to prevent removal of said plate and to serve as fulcrums for said arms, and means for drawing the upper ends of said arms together.

In testimony whereof I have hereunto set my hand in the presence of two subscribing witnesses.

DANIEL W. SMITH.
